UNITED STATES PATENT OFFICE.

JOHN J. CREED, OF MCDONOGHVILLE, LOUISIANA, ASSIGNOR OF TWO-THIRDS TO CHARLES M. BABCOCK AND WILLIAM A. BELL, OF SAME PLACE.

DRAFT-GEAR FOR FREIGHT-CARS.

SPECIFICATION forming part of Letters Patent No. 680,130, dated August 6, 1901.

Application filed March 2, 1901. Serial No. 49,623. (No model.)

To all whom it may concern:

Be it known that I, JOHN J. CREEED, a citizen of the United States, residing at McDonoghville, in the parish of Jefferson and State of Louisiana, have invented certain new and useful Improvements in Draft-Gear for Freight-Cars; and I do hereby declare the following to be a full, clear, and exact description of the invention, such as will enable others skilled in the art to which it appertains to make and use the same.

My invention relates to improvements in draft-rigging, and more particularly to the continuous type.

It consists of a draw-head, draw-bars secured thereto, and means for supporting said parts upon the frame of a car; and it has for one of its objects the provision of such supporting means as may be readily removed or secured to the draft-sills of a car-frame without removing the load of a loaded car.

It also has other objects in view, and comprises certain other novel constructions, combinations, and arrangements of parts, as will be hereinafter more fully described and claimed.

In the accompanying drawings, Figure 1 represents a side elevation of a portion of a car-frame with a draft appliance secured thereto embodying the features of my invention. Fig. 2 is an inverted plan view of the same, and Fig. 3 is a longitudinal vertical section on line $\alpha\alpha$ of Fig. 1.

Referring to the drawings by numerals, 1 indicates the end sill of a car-frame, and 2 2 indicate the draft-sills thereof. A shank, as 3, is provided centrally of said draft-sills and beneath the same, and any preferred form of coupler, as 4, is secured to the outer end of the said shank. A plate, as 5, is adapted to pass transversely through said shank 3, as usual, and through the elongated slots in the ends of the draw-bars 6 6, whereby the couplers at either end of the car will be connected, the draft apparatus at both ends of the car being similar. A bolt or pin, as 7, is secured within the inner end of shank 3 and extends rearwardly therefrom through bearing-box 8 and is provided with a nut threaded upon its inner end, as 9. Interposed between the end

of shank 3 and box 8 and coiled about said bolt 7 is provided a spring, as 10, and a similar spring 11 is provided between said box 8 and nut 9, whereby revolution of said nut will tend to increase or decrease the tension 55 of said springs.

Box 8 is formed of four walls extending downwardly from and formed integral with a draft or follower plate 12. This follower-plate is formed with laterally and vertically 60 extending attaching pieces or flanges, and each horizontal flange is adapted to extend entirely across the width of the lower face of draft-sill 2, while the other vertical flanges extend entirely across the inner vertical walls 65 of the sills, whereby securing means, as bolts 13 13, may be passed either vertically or horizontally through said draft-sill for holding said draft or follower plate 12 in position, or said securing means may be passed both vertically and horizontally through said draft-sill and flanges. The vertically - arranged flange of each of the followers 12 is adapted to abut against the end sill 1 and extend 70 backwardly as far as desirable, and the horizontally-arranged flanges of said plate 12 extend forwardly across end sill 1 and to the outer edge of buffer-block 14 and rearwardly an equal distance with the vertical flange.

A strip of metal or other suitable material, 80 as 15, may be secured at its ends to the outer ends of the horizontal flanges of the follower-plate 12 and to the buffer-block 14 for supporting the outer end of shank 3 and the weight of the coupler 4. 85

The great advantages of my improved construction will be readily apparent to those skilled in the art. The parts are so formed and arranged as to give the draw-bars a slight resiliency and at the same time hold them 90 rigid upon being subjected to strain, whereby the parts are less liable to breakage.

Another great advantage of my improved construction is the formation of the follower-plate, whereby broken parts of the draft ap- 95 pliance may be replaced by new ones whenever an accident occurs, without regard to whether the car is loaded or not. Should an accident occur to a loaded car, the broken parts may be removed and a new draft- 100

plate placed upon the draft-sills and secured thereto by passing securing means through said sills horizontally without removing the load from the car, and the draft-beam is 5 ready for action. It is probably better, when a convenient time arrives, to add also securing means passed vertically through said draft-sills; but with my improved construction the horizontally-arranged securing means 10 have been found sufficient for use until such convenient time arrived, thus obviating the necessity of the expense and annoyance of unloading and reloading a car every time an accident occurs to its draft-rigging.

15 Although I have described in detail one specific embodiment of my invention, yet I shall feel at liberty to deviate from the exact size, shape, and minor details of construction of the parts within the spirit and scope of 20 my invention.

Having thus fully described my invention, what I claim as new, and desire to secure by Letters Patent, is—

1. A draft-rigging for cars comprising a 25 draft-plate or follower formed with a central bearing-box, vertically-extending attaching-flanges secured thereto projecting beyond the said bearing-box in each direction for bracing it each way and extending between 30 the draft-sills of the car, laterally-extending horizontal flanges extending along the under sides of the said draft-sills on each side of the bearing-box and forwardly under the end sill, and means for holding the coupler of the car in 35 position with respect to the said bearing-box, the structure being such that the draft or follower plate may be secured to the draft-sills by vertical or horizontal bolts passing either through the vertical or horizontal at- 40 taching-flanges or through both and will be equally braced against strains in either direction, substantially as described.

2. A draft-rigging comprising a draft-plate or follower made up of a central bearing-box 45 having a bearing formed therein for receiving the tail-bolt of the coupler, elongated laterally-projecting horizontal attaching-flanges secured to the bearing-box extending each

way therefrom and adapted to fit upon the under surface of the draft-sills of a car or 50 other vehicle and extend forwardly under the end sill thereof, elongated vertically-extending attaching-flanges extending each way from the bearing-box and adapted to fit upon the inner faces of opposing draft-sills, springs 55 interposed between the said bearing-box and the coupler mechanism for pulling on said bearing-box in either direction, and bolts for securing the flanges to the said sills, the structure being such that if the draft-plate 60 should become broken while the car or other vehicle is in use a new one can be put in position and the bolts for attaching the same may be placed through the vertical flanges for securing them to the draft-sills without 65 removing the car-body from the said sills, substantially as described.

3. A draft-rigging for cars or similar vehicles comprising a draft or follower plate formed with a central body portion having a 70 bearing therein to receive the tail-bolt of a coupler, laterally-extending horizontal attaching-flanges upon each side of the body portion and vertically-extending attaching-flanges adapted to fit against the lower and 75 inner faces of the draft-sills respectively of the vehicle, the horizontal flanges extending forward beneath the buffer-blocks to its outer edge while the vertical flanges are cut away so as to be shouldered against the end sill 80 of a car, a coupler carried by the follower-plate, having its tail-bolt extending through the bearings therein, springs interposed be- 85 tween the coupler and the bearing-box on one side thereof and between the tail-bolt end nut and the bearing-box on the other side and means for connecting the couplers at each end of the car with each other, substan- 90 tially as described.

In testimony whereof I hereunto affix my 90 signature in presence of two witnesses.

JOHN J. CREED.
